COMBINED BALL POINT PEN AND LIGHTER

Taro Yanai, 6-15 Ohtemachi, 3-chome,
Maebashi-shi, Gunma-ken, Japan

Filed Apr. 17, 1973, Ser. No. 352,025

Term of patent 14 years

Int. CL D19—06; D27—05

U.S. Cl. D27—38

FIG. 1

FIG. 2

FIG. 3

FIG. 4

FIG. 1 is a perspective view of a combined ball point pen and lighter from one side thereof embodying my new design;

FIG. 2 is a perspective view of the opposite side of the combined ball point pen and lighter of FIG. 1;

FIG. 3 is an exploded perspective view of the combined ball point pen and lighter of FIGS. 1 and 2, with the cap thereof omitted for purposes of disclosure; and

FIG. 4 is an enlarged view of the upper member of the combined ball point pen and lighter shown in FIG. 3 viewed from the right, and inverted.

I claim:

The ornamental design for a combined ball point pen and lighter, as shown and described.
